The ornamental design for an attachable elastic shoe sleeve, as shown and described.

DESCRIPTION

FIG. 1 is a perspective view of an attachable elastic shoe sleeve depicted in a state of use as worn over a shoe, showing my new design;

FIG. 2 is a perspective view of the attachable shoe sleeve;

FIG. 3 is a front view thereof;

FIG. 4 is a rear view thereof;

FIG. 5 is a left side view thereof with a right side view being a mirror image; and,

FIG. 6 is a top view thereof with a bottom view being a mirror image.

The broken line showing of a shoe in FIG. 1 is for the purpose of illustrating environmental structure and forms no part of the claimed design.
